UNITED STATES PATENT OFFICE.

JOHN READING, OF AKRON, OHIO.

CLOTH-MEASURING MACHINE.

SPECIFICATION forming part of Letters Patent No. 448,368, dated March 17, 1891.

Application filed October 22, 1890. Serial No. 368,918. (No model.)

To all whom it may concern:

Be it known that I, JOHN READING, a citizen of the United States, residing at Akron, in the county of Summit and State of Ohio, 5 have invented a certain new and useful Improvement in Wall-Paper-Border-Measuring Machines, of which the following is a specification.

Wall-paper borders, as is well known, are 10 printed of different widths or "brands" on strips of paper of substantially the same width, and in retailing less than one roll are unrolled by hand, measured, severed from the roll, and rerolled. This process is objectionable, be- 15 cause of the time and labor required, and, again, because the repeated handling tends to deface and injure the paper, and, finally, as often occurs, mistakes are made in the amount actually cut off.

20 The object of my invention is to produce a simple and compact machine by which the border-roll shall be mechanically unrolled, measured, rerolled, and severed, and its amount accurately indicated, so that a mis- 25 take is avoided.

To this object my invention consists of the peculiar and novel construction, arrangement, and combination of mechanical parts herein- 30 after set forth, and then specifically pointed 35 out in the claims, reference being had to the accompanying drawings, forming a part of this specification.

In the accompanying drawings, in which similar letters of reference indicate like parts, 35 Figure 1 is a plan of my machine with a part of the graduated scale broken away to show the index-moving screw; Fig. 2, an end elevation, and Fig. 3 a vertical section at the line 40 xx of Fig. 1.

45 Referring to the drawings, A is a case, usually of wood, in form of a shallow box open at the top, and upon which is a case B, consisting of three sides similarly constructed, having its back hinged to the back of the case 50 A, and with its ends registering with the ends of said case. The internal length of the case A slightly exceeds the extreme length of wall-paper-border rolls, and between its ends is a partition C, which extends from a line in the 55 front wall of the case and at a distance exceeding the diameter of roll of border below its front upper edge, horizontally backward

about the same distance, thence upward, slightly inclined backward from a perpendicular until near the top of the case, when it 55 again turns backward, slightly inclined upward from a horizontal line to said top. This forms a trough in which the roll of border is placed and a platform over which it is led to be measured and rerolled.

6c

In the case A is journaled a roll D, and directly above it in the case B is journaled a similar roll E, both having a flexible covering, as felt, and arranged, when the case B is lowered, to press against each other and be 65 revolved by the friction of the strip of border-paper which passes between them. Parallel with and above the roll E is journaled a screw F, the journal of which extends through one side of the case B, and bears a pinion F', 70 which meshes in a larger pinion E' on the end of the shaft of the roll E. Across the top of the case B above the screw F is a bar G, bearing numbered graduate-marks, parallel with and back of which is a rod H. Mounted and 75 free to slide on the rod H is a short lever I, which has segmental under screw-threads that mesh in the threads of the screw F, and a pointer that passes above and along the graduated bar G, and is arranged by a knob 80 or other suitable handle to be rocked upward sufficiently to release it from the screw F. Back of the roll D in the case A is a roll J, the journal of which projects through one side of the case A and bears a pinion J', 85 which meshes in a larger gear-wheel K, journaled on a stud projecting from the case A, and provided with a handle by which it can be revolved. Extending across the front of the frame B above the upper part of the partition C is a bar I', having a longitudinal slot 90 through which a knife can be inserted to sever the border-roll.

In operation a roll of border-paper, as L, is placed in the trough made by the partition 95 C, and the end is then carried forward over the roller D, and sufficiently attached by winding about the roll J. This operation is facilitated by raising the frame B, so as to permit the rolls E D to separate. The frame 100 B is then lowered, so as to compress the rolls E D on the strip of border-paper, and the lever I is, by raising free from the screw F, passed backward to the initial point of the

scale G. The wheel K is then actuated by hand and winds the strip of border-paper as it unwinds from the roll L about the roll J. By the passage of the strip of paper between the 5 rolls E D they are turned by friction, and by means of the wheels E' D' turn the screw F and cause the lever I to travel along it until its pointer indicates on the graduated bar G that the requisite amount has been measured, 10 when the movement is stopped, and a knife inserted in and passed through the slot in the bar I severs the paper.

I claim as my invention—

1. In a machine for measuring strips of fabric, the combination, with two frames hinged at one side and arranged to register with each other, of two oppositely-disposed rollers severally mounted in said frames and arranged 15

to engage and be turned by the passage of the fabric between them, and a registering device 20 arranged to be operated by one of said rollers, substantially as shown and described.

2. The herein-described machine embodying the following elements, viz: the case A, case B, partition C, rollers D E, screw F, lever I, graduated scale G, slotted bar I', and spindle J, all arranged to operate as herein-before described and shown, and for the purpose specified.

In testimony that I claim the above I hereunto set my hand.

JOHN READING.

In presence of—

C. E. HUMPHREY,
C. P. HUMPHREY.
